UNITED STATES PATENT OFFICE.

ALFRED HORNER STRINGE, OF CHICAGO, ILLINOIS, ASSIGNOR TO COMMERCIAL FURNITURE COMPANY, OF CHICAGO, ILLINOIS.

DESIGN FOR A CHAIR.

Application filed January 20, 1923. Serial No. 4,945. Term of patent 7 years.

To all whom it may concern:

Be it known that I, ALFRED H. STRINGE, a citizen of the United States, residing at Chicago, in the county of Cook and State of Illinois, have invented a new, original, and ornamental Design for Chairs, of which the following is a specification, reference being had to the accompanying drawing, forming part thereof.

The figure is a perspective view of a chair, showing my new design.

I claim:

The ornamental design for a chair, as shown.
